UNITED STATES PATENT OFFICE.

WILLIAM A. GEIGER, OF CHICAGO, ILLINOIS, ASSIGNOR TO WILLIAM H. MINER, OF CHAZY, NEW YORK.

HAND BRAKE FOR RAILWAY CARS.

Application filed March 6, 1922. Serial No. 541,337.

To all whom it may concern:

Be it known that I, WILLIAM A. GEIGER, a citizen of the United States, residing at Chicago, in the county of Cook and State of Illinois, have invented a certain new and useful Improvement in Hand Brakes for Railway Cars, of which the following is a full, clear, concise, and exact description, reference being had to the accompanying drawings, 10 forming a part of this specification.

This invention relates to improvements in hand brakes for railway cars.

In the operation of hand brakes of the vertical staff type for railway cars, difficulty has 15 been experienced heretofore, due to the binding of the staff when released. Binding of the staff is frequently caused by bulging of the end wall of the car or by bending of the staff, with the result that, even though the 20 brake is released in the usual manner, the chain will not become fully slack so that the brake shoes will remain in contact with the wheels.

The object of my invention is to provide 25 an arrangement especially adapted for hand brakes of the vertical staff type wherein provision is made for positively insuring the full and complete release of the hand brake mechanism to the end that the brake shoes 30 may be freely disengaged from the wheels to minimize wear and reduce the tractive effort required of the locomotive.

In the drawing forming a part of this 35 specification, Figure 1 is a horizontal sectional view through the end wall of the car and showing my improvements in connection therewith. Figure 2 is a vertical, sectional view of the structure illustrated in Figure 1 and corresponding to the broken 40 section line 2-2 thereof. In Figure 1 the operating handle is shown in operative position, whereas in Figure 2 it is shown in depending inoperative position. Figure 3 is a detail plan view of a collar employed in connection with the locking dog for the purpose 45 hereinafter described. Figure 4 is a plan view of the articulated locking dog. Figure 5 is a view similar to Figure 4 but showing a part of the release handle proper in horizontal section. Figure 6 is a horizontal, sectional view corresponding substantially to the section line 6-6 of Figure 2, illustrating the formation and location of certain teeth 50 on the fixed bracket to cooperate with the collar hereinbefore referred to. And Figure 55

7 is a vertical, detail, sectional view of the locking dog corresponding to the section line 7-7 of Figure 4.

In said drawing, the end wall of the car is indicated at 10 and to which is secured a 60 housing or bearing bracket designated generally by the reference character A. Said bracket A is provided with a rear wall 11, riveted or otherwise rigidly secured to the car wall 10, with a bottom web or wall 12 extending horizontally and provided with a journal bearing 13, an intermediate web or partition 14 and vertical flanges 15 and 16. A cap or cover plate 17 is also employed preferably riveted to the main portion of the 70 bracket casting A. A portion of the usual vertical brake staff is indicated at 18, the same having a squared or other noncircular cross section at the top thereof, on which is rigidly fitted a ratchet wheel 19 having vertically extending peripheral ratchet teeth 20. The ratchet wheel 19 is provided at the bottom thereof with a journal 19^a rotating in the bearing 13 and at the top is provided with another journal 19^b. Oscillatably 80 mounted on the journal bearing 19^b is a carrier or fulcrum member designated generally by the reference character B. Said carrier B has a substantially annular depending flange 21 from which are extended laterally 85 wings 22-22. Pivotedly mounted between the wings 22 on a horizontal pivot bolt 23 is an operating handle or lever 24.

The handle 24 is provided at the top end thereof with a longitudinally extending 90 socket 25 within which is slidably mounted a pawl 26 normally impelled outwardly by means of the spring 27. The arrangement of the handle and pawl is such that, when the handle is elevated to a horizontal position 95 as shown in Figure 1, the pawl is operatively engaged with the ratchet wheel 19 and when the handle is released, it automatically falls to a depending vertical inoperative position, as shown in Figure 2. With this arrangement, it is evident that the staff may be rotated in a winding direction step by step 100 in the usual manner.

To hold the staff against accidental reverse rotation, I employ a preferably articulated locking dog consisting of the two sections 105 28 and 29. The latter is forked as indicated at 29^a-29^b best in Figure 7, and between which is received the reduced end 28^a of the other section of the dog. The in- 110

terfiting sections 28^a and 29^a are provided with alined perforations adapting them to be oscillatably mounted on a vertically extending bolt 30 which is supported in the bracket 5 or housing, as best shown in Figure 2. Between the forked sections 29^a, the handle or lever element proper of the dog is formed with a curved recess 31 with terminal shoulders 32—32 located opposite corresponding 10 shoulders 33—33 on the other element of the dog. As best indicated in Figure 5, a predetermined amount of clearance is allowed between the opposed shoulders 32 and 33 so that the dog proper 28 is adapted to oscillate a limited amount, independently of the handle or lever proper 29.

The dog proper 28 is provided with a single tooth 34 adapted to cooperate with the teeth 20 of the ratchet wheel and is normally 20 held in yielding engagement therewith by means of a suitable spring 35 interposed between the dog proper 28 and the back wall of the bracket A.

The upper fork 29^a of the handle or lever proper 29 of the releasing dog, is formed with a square or other non-circular socket 36 within which is received a correspondingly shaped section 37 at the lower end of a collar or bushing designated generally by 30 the reference character C. The latter, immediately above the square section 37 is of cylindrical form as indicated at 38 and is rotatably and vertically movably mounted in a suitable bearing provided therefor in the 35 web 14 of the bracket as indicated at 39. With this arrangement, it is evident that the collar or bushing C will always move in unison with the handle or lever proper 29.

Above the web 14 of the bracket A, the 40 collar or bushing C is provided with a laterally extended annular flange 40 on the under side of which are a plurality of circumferentially spaced depending teeth 41—41. The latter are adapted to cooperate 45 with correspondingly upwardly extending teeth 42—42 on the upper face of the web 14, as best shown in Figure 6. An expansion coil spring 43 is attached to the bolt 30 and the collar C, as shown in Figure 2, in 50 such a manner as to normally turn the collar in a clockwise direction as viewed in Figure 1 and also to normally press it downwardly so that the collar and the lever proper 29 will normally be held in the full line 55 positions indicated in Figure 1. In this position of the parts, the teeth 41 of the collar C are to one side of the fixed teeth 42. The flange 40 of the collar C is cut away as indicated at 44, on that side immediately adjacent the bottom annular flange 45 of the carrier or 60 fulcrum member B so that the latter is free to rotate with respect to the collar C during the winding up or application of the brake. Said bottom flange 45 of the carrier B is 65 provided on the upper face thereof with a

plurality of circumferentially spaced double cam-acting lugs 46—46 adapted to ride under the flange 40 of the collar C under certain conditions, as hereinafter described.

The operation of the hand brake in winding up will be fully understood from the preceding description, it being clear that the locking dog proper 28 will automatically ride over the ratchet teeth and drop into place without any actuation of the collar C 70 or release lever proper 29. When it is desired to release the brake, the brakeman pulls the release lever proper 29 outwardly or away from the wall of the car to the dotted line position shown in Figure 1. This movement of the release lever proper induces a corresponding movement not only of the dog proper 28 but also of the collar C. As the latter is rotated in a counterclockwise direction as viewed in Figure 1, the teeth 41 thereof are caused to ride up and over the fixed teeth 42 and engage with the latter automatically so as to lock the collar C against rotation back to normal position. In this manner the locking dog proper 28 and the release lever proper 29 are held in their dotted line positions shown in Figure 1. Consequently, the brake staff, even though it may stick or bind during the latter portions of the release of the brakes, due to binding on the staff, will nevertheless be free to continue its rotation in an unwinding direction as the staff, brake chain and other parts of the brake rigging are jarred and rattled as soon as the car is placed in motion. This results in the brake shoes being fully disengaged from the wheels either shortly after the car is started in motion and the parts will be held in this condition until the brakes are subsequently again applied.

When the brake is later applied, the brakeman elevates the handle 24 and pulls the same toward him during which action the carrier B will be correspondingly rotated, thus causing the cam 46 thereof to ride under the annular flange 40 of the collar C and thus lift it so as to disengage the teeth 41 thereof from the fixed teeth 42, whereupon the collar will be free to rotate back to its normal position, and also be depressed under the action of the spring 43, thus restoring the locking dog and associated parts to their normal operative condition.

I have herein shown and described what I now consider the preferred manner of carrying out the invention but the same is merely illustrative and I contemplate all changes and modifications that come within the scope of the claims appended hereto.

I claim:

1. In a hand brake having a vertical staff and a ratchet wheel rigid therewith, the combination with means for rotating said staff in a winding direction; of a locking

- dog automatically cooperable with said ratchet wheel to hold the same against rotation in a reverse direction; a release lever articulated with respect to said dog and 5 adapted to move the latter to inoperative position; and means automatically operable to retain said release lever in its released position to thereby hold the dog out of engagement with the ratchet wheel.
- 10 2. In a hand brake having a vertical staff and a ratchet wheel rigid therewith, the combination with means for rotating said staff in a winding direction; of a release lever; a dog movable independently of the 15 release lever, adapted to be actuated by the latter to an inoperative position; and means automatically operable to hold the release lever in its released position to thereby hold the dog out of engagement with the ratchet 20 wheel.
3. In a hand brake having a vertical staff and a ratchet wheel rigid therewith, the combination with means for rotating said staff in a winding direction; of a release 25 lever; a dog movable independently of the release lever, adapted to be actuated by the latter to an inoperative position; means automatically operable to hold the release lever in its released position to thereby hold 30 the dog out of engagement with the ratchet wheel; and means for releasing said retaining means upon actuation of said rotating means.
4. In a device of the character described, 35 the combination with a vertical brake staff having a ratchet wheel rotatable in unison therewith; of means for rotating said staff step by step in a winding direction including a carrier oscillatably mounted with respect to the staff and a pawl operating 40 lever; of a pivotally mounted spring-influenced locking dog cooperable with said ratchet wheel to normally prevent rotation of the latter in an unwinding direction; a 45 release lever movable independently of the dog and cooperable with the latter to move it to inoperative position; and spring-influenced means cooperable with said release lever to hold it in inoperative position when 50 manually so moved.
5. In a device of the character described, the combination with a vertical brake staff having a ratchet wheel rotatable in unison therewith; of means for rotating said staff step by step in a winding direction including a carrier oscillatably mounted with respect to the staff and a pawl operating lever; of a pivotally mounted spring-influenced locking dog cooperable with said ratchet wheel to normally prevent rotation 55 of the latter in an unwinding direction; a release lever movable independently of the dog and cooperable with the latter to move it to inoperative position; spring-influenced means cooperable with said release lever to hold it in inoperative position when manually so moved; and means on said carrier cooperable with said last named means to automatically disengage the latter upon movement of said carrier. 60
6. In a device of the character described, the combination with a bracket adapted to be secured to a car wall; of a vertical brake staff having a ratchet wheel rotatable therewith; a carrier oscillatably mounted with 65 respect to said staff; a pawl operating gravity drop handle mounted on said carrier and adapted to cooperate with said ratchet wheel; a locking dog proper pivotally mounted on said bracket and normally cooperable with said ratchet wheel; a release lever cooperable with said dog proper and having a limited amount of oscillation with respect thereto; a spring-pressed toothed collar movable in unison with said release 70 lever; fixed teeth on said bracket with which the teeth of said collar are adapted to engage when the release lever is manually moved to inoperative position; and means on said carrier cooperable with said collar to release the latter upon oscillation of the carrier. 75
- In witness that I claim the foregoing I have hereunto subscribed my name this 17th day of February, 1922.
